[57] CLAIM

The ornamental design for a cutting head for a trimmer, as shown and described.

DESCRIPTION

FIG. 1 is a top perspective view of the cutting head for a trimmer, showing the cutting lines in phantom lines;

FIG. 2 is a front elevational view thereof;

FIG. 3 is a side elevational view thereof and a mirror image of the opposite side thereof;

FIG. 4 is a rear elevational view thereof;

FIG. 5 is a top plan view thereof; and,

FIG. 6 is a bottom plan view thereof.

The broken line showing of cutting line is for illustrative purposes only and forms no part of the claimed design.
